PLUG-IN POWER SUPPLY

John Muller, Massapequa, and James Gietzen, Smithtown, N.Y., assignors to Dynamic Instrument Corp., Plainview, Long Island, N.Y.

Filed Apr. 20, 1972, Ser. No. 246,099

Term of patent 14 years

Int. Cl. D13—02

U.S. Cl. D26—15 A

FIG. 1 is a perspective view of a plug-in power supply showing our new design;

FIG. 2 is a top plan view of the plug-in power supply shown in FIG. 1;

FIG. 3 is a bottom plan view of the plug-in power supply shown in FIG. 1;

FIG. 4 is a side elevational view of the plug-in power supply of FIG. 1; and

FIGS. 5 and 6 are front and rear elevational views of the plug-in power supply of FIG. 1.

We claim:

The ornamental design for a plug-in power supply, as shown.
